(57) **CLAIM**

The ornamental design for a dental capsule, as shown and described.

DESCRIPTION

FIG. 1 is a perspective view showing the new design for a dental capsule.

FIG. 2 is a right view thereof;

FIG. 3 is a left view thereof;

FIG. 4 is a top view thereof;

FIG. 5 is a bottom view thereof;

FIG. 6 is a front view thereof; and,

FIG. 7 is a back view thereof.

The broken lines form no part of the claimed design, and any shading is provided to illustrate contour only and is not an indication of texture, gloss, etc.

The broken lined showing portions of a dental capsule are included for illustrating environmental structure and form no part of the claimed design.
